Primary Examiner—Holly Baynham
Attorney, Agent, or Firm—Dressler, Rockey, Milnamow & Katz, Ltd.

[57] CLAIM

The ornamental design for a gutter bracket, as shown and described.

DESCRIPTION

FIG. 1 is a perspective view of a first embodiment of a gutter bracket showing my new design;

FIG. 2, on a smaller scale, is an end view thereof, as seen from the left end in FIG. 1;

FIG. 3, on a similar scale, is an end view thereof, as seen from the right end in FIG. 1;

FIG. 4, on a similar scale, is a top view of the gutter bracket shown in FIG. 1;

FIG. 5, on a similar scale, is a side view thereof, as seen from the nearer side in FIG. 1, the other side thereof being a mirror image of the side shown;

FIG. 6, on a similar scale, is a bottom view of the gutter bracket shown in FIG. 1;

FIG. 7 is a perspective view of a second embodiment of a gutter bracket showing my new design;

FIG. 8, on a smaller scale, is an end view thereof, as seen from the left end in FIG. 7;

FIG. 9, on a similar scale, is an end view thereof, as seen from the right end in FIG. 7;

FIG. 10, on a similar scale, is a top view of the gutter bracket shown in FIG. 7;

FIG. 11, on a similar scale, is a side view of the second embodiment thereof, as seen from the nearer side in FIG. 7, the other side thereof being a mirror image of the side shown; and,

FIG. 12, on a similar scale, is a bottom view of the gutter bracket shown in FIG. 7.
